PRESSING MACHINE

Hyman E. Cole, Valley Stream, N.Y., assignor to New York Pressing Machinery Corporation, Paterson, N.J., a corporation of New York

Filed June 3, 1959, Ser. No. 817,909

8 Claims. (Cl. 38—17)

This invention relates generally to apparatus for pressing textiles, and is especially concerned with a unique improvement for use with a steam pressing machine.

As is well known to those versed in the art, conventional steam pressing machines are subject to certain difficulties in operation, such as movement of the head causing a scraping action against the buck which wrinkles and distorts the fabric, and also that of suction between the head and fabric during pressing engagement, which causes the fabric to be lifted away from the buck upon elevation of the head. In addition, certain prior art pressing-machine devices permitted condensation of steam to cause water spots and stains on the fabric being pressed.

Accordingly, it is an object of the present invention to provide a highly advantageous improvement, for use in pressing machines, which overcomes the above-mentioned difficulties, eliminating scraping and lifting of the fabric being pressed by the head, and consequent wrinkles and distortion of the fabric, and which effectively prevents condensation of steam likely to cause water spots and stains.

It is a further object of the present invention to provide a device having the advantageous characteristics mentioned in the preceding paragraphs, which is adapted to be quickly and easily attached to conventional pressing-machine apparatus, and to afford the above-mentioned advantageous results while enabling the pressing apparatus to be operated in a simple and more rapid manner.

It is still another object of the present invention to provide a device of the type described which is extremely simple in construction, durable and reliable in operation throughout a long useful life, and which can be economically manufactured and installed for sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claim.

In the drawings:

Fig. 1 is a partial top plan view showing a pressing machine employing a device constructed in accordance with the teachings of the present invention;

Fig. 2 is a sectional elevational view taken substantially along the line 2—2 of Fig. 1, illustrating the head of a pressing machine carrying an attachment of the present invention and in pressing relation with the buck of a pressing machine;

Fig. 3 is a sectional elevational view similar to Fig. 2 showing the head of the pressing machine in an intermediate stage of movement out of its pressing relation with the buck; and

2

Fig. 4 is a sectional elevational view similar to Figs. 2 and 3, showing the head of the pressing machine completely removed from its pressing relation with the buck.

Referring now more particularly to the drawings, and specifically to Fig. 4 thereof, a pressing-machine frame is there designated 10, and includes a conventional upwardly facing, fixed buck 11. Rearward of the buck 11, the frame 10 is provided with an upstanding journal support 12. An arm 13 is pivotally connected to the upstanding journal support 12 by a journal pin or shaft 14; and the arm 13 extends generally forward and upward from its journal 14 as seen in Fig. 4. However, the arm 13 is swingable relative to the frame 10 about the axis of the journal pin 14.

In Fig. 1 it may be observed that the arm 13 includes a pair of forward-end extensions or furcations 15, to the underside of which is fixedly secured an elongate head 16, as by fasteners 17. As seen in Fig. 1, the head 16 is of laterally elongate configuration, in the conventional manner; and the buck 11 is also laterally elongate in the conventional manner. Suitable manually actuatable operating controls 18 may be provided on the upper side of the head 16.

As thus far described, the structure is that of a conventional pressing machine, wherein the head 16 is mounted for swinging movement with the arm downward toward the buck 11 into pressing relation therewith, and upward movement away from the buck and out of pressing relation.

The improvement of the present invention is generally designated 20 and includes a plate 21 of heat-conductive material, such as aluminum, interposed between the buck 11 and head 16 for conforming sandwiched engagement therebetween upon movement of the head into pressing relation with the buck, as seen in Fig. 2. The plate 21 is preferably perforated or formed with apertures 22 for the passage therethrough of steam. An upstanding peripheral wall or flange 23 is preferably provided extending completely about the plate 21 conformable to and receiving the head 16 when the latter is in its pressing relation. The flange 23 may advantageously be formed integrally with the plate 21 of aluminum or other suitable heat-conductive material.

On the rearward side of the head 16, at spaced locations therealong, are provided a pair of hinges 25, each having one hinge plate fixed to the adjacent region of the plate flange 23, and having its other hinge plate fixed to the rearward side of the head 16 by an extension or bracket 26. The hinges 25, and their brackets 26, are advantageously fabricated of heat-conductive material for transmitting heat from the heated head 16 to the plate 21. The pivotal axes of the hinges 25 are in substantial alignment with each other so as to mount the plate 21 for swinging movement relative to the head. Specifically, the plate 21 is swingable about the aligned axes of hinges 25 between the position of Fig. 2 in facing engagement with the underside of the head 16, and the position of Fig. 4 spaced below and away from the underside of the head.

On the forward side of the head 16, at laterally spaced locations therealong, are means designated 28 connecting the forward side of the head to the forward region of the plate and limiting swinging movement of the latter away from the head about the axes of hinges 25. In particular, each of the connecting means 28 may include an angle bracket 29 fixed to the forward portion of plate flange 23 and extending upward therefrom. Carried by the upper end of each bracket 29 and projecting upward therefrom is a headed bolt or pin 30, which may be fixed relative to the bracket 29. An additional angle bracket 31 may be fixed to the forward side of the head 16 adjacent to each bracket 29 and provided with

a forwardly extending portion loosely receiving the pin 30 for sliding movement of the latter through the bracket 31. Resilient means, in the form of a coil compression spring 32, is circumscribed about each pin 30 and has its opposite ends in bearing engagement with the brackets 29 and 31, respectively, and compressed therebetween to resiliently urge the pin 30 downward to the position limited by engagement of the head of the pin 30 with the bracket 31. This condition is illustrated in Fig. 4. The plate 21 is swingable toward the head 16 to the position of Fig. 2 by compression of the spring 32.

From the condition of Fig. 2, wherein is seen a fabric or piece 34 being pressed, it will be noted that the plate 21 is sandwiched between the head 16 and buck 11, in pressing engagement with the fabric 34. Upon cessation of the pressing operation of Fig. 2, the head 16 is elevated, in the direction of the arrow 35 of Fig. 3, which simultaneously elevates the rearward side of the plate 21, the latter being directly hinged to the head. Thus, the plate 21 is raised from pressing engagement with the fabric 34 initially at its rearward side and progressively forward, the forward side of the plate 21 remaining in pressing relation with the piece 34 appreciably after upward movement of the head 16 has been initiated. Of course, continued upward movement of the head 16 raises the entire plate 21, including the forward region thereof from the buck 11 and fabric 34, the condition illustrated in Fig. 4.

During this above-described upwardly movement of the head 16 and removal of the plate 21 from its pressing engagement with the fabric 34, air is gradually permitted to enter between the plate 21 and fabric 34 from the rearward side to prevent or destroy any vacuum or suction therebetween. However, the plate 21 remains quite hot, although being spaced from the heated head 16, by means of heat conduction from the head to the rearward region of the plate, as through the hinges 25 and brackets 26, so that steam will not be condensed and water spots and stains will be eliminated.

Relative movement of the forward region of the plate 21 with respect to the buck 11 during the initial upward movement of the head 16 is negligible, so that no scraping or creasing of the fabric occurs. If desired, the aligned axes of hinges 25 may be located relative to the axis of journal pin 14 to obtain a substantially stationary position of the forward plate edge relative to the buck 11 during the initial upward movement of the buck, as by locating the journal pin 14 such that the head 16 and hinges 25 swing upward and slightly forward at the inception of upward head movement.

From the foregoing, it is seen that a pressing-machine apparatus is provided which fully accomplishes its intended objects and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

1. In a pressing machine including a buck and a head mounted for swinging movement into and out of pressing relation with said buck, the improvement comprising a plate adapted to be interposed between said buck and head and being sandwiched therebetween when said head is moved into pressing relation with said buck, hinge means on one side of said head connecting said plate

directly to said head for swinging movement toward and away from the latter, and connecting means on the other side of said head and connected to said plate for affording limited plate movement away from said head, whereby said plate adjacent to said other head side is adapted to remain in pressing relation with said buck after said plate adjacent to said one head side is out of said pressing relation.

2. The improvement according to claim 1, in combination with resilient means operatively associated with said connecting means to urge said plate away from said head.

3. The improvement according to claim 1, said plate and hinge means being of heat-conductive material to transmit heat from said head to said plate and prevent condensation of steam upon head movement away from said buck.

4. A pressing machine comprising a buck, a head over said buck, journal means mounting said head for swinging movement toward and away from said buck, a plate interposed between said buck and head and sandwiched therebetween when said head is moved toward said buck, hinge means on one side of said head connecting said plate directly to said head for swinging movement of said plate toward and away from said head, and connecting means on the other side of said head and connected to said plate affording limited plate movement away from said head, whereby said plate adjacent to said other head side is adapted to remain in position on said buck after said plate adjacent to said one side is moved with said head away from said buck.

5. A pressing machine according to claim 4, said hinge means and journal means being located relative to each other so that said other plate side remains at substantially the same position on said buck until said one plate side is appreciably removed from said buck when said head is moved away from said buck.

6. A pressing machine according to claim 4, said plate and hinge means being of heat-conductive material to transmit heat from said head to said plate and prevent condensation of steam upon head movement away from said buck.

7. A pressing machine according to claim 4, in combination with resilient means operatively associated with said connecting means to urge said plate away from said head.

8. An attachment for a pressing machine having a buck and a head mounted for swinging movement into and out of pressing relation with said buck, said attachment comprising a perforate plate having a peripheral flange and adapted to be interposed between said head and buck with said flange surrounding said head, hinge means of heat-conductive material connected to one side of said plate and adapted for direct connection to the adjacent side of said head to mount said plate for swinging movement toward and away from said head, and resilient connecting means on the other side of said plate and adapted for connection to said head for resiliently urging said plate toward a limiting position of movement away from said head, whereby said other side of said head is adapted to remain in position relative to said buck after said one side of said plate has been moved appreciably away from said buck by movement of said head.
